UNITED STATES PATENT OFFICE.

JOHN ANDREW KREMER, OF AURORA, ILLINOIS.

INTERNAL-COMBUSTION ENGINE.

1,172,612.

Specification of Letters Patent. Patented Feb. 22, 1916.

Application filed January 2, 1915. Serial No. 140.

To all whom it may concern:

Be it known that I, JOHN ANDREW KREMER, a citizen of the United States, residing at Aurora, in the county of Kane and State of Illinois, have invented a new and useful Internal-Combustion Engine; and I do hereby declare the following to be a full, clear, and exact description of the invention, such as will enable others skilled in the art 10 to which it appertains to make and use the same.

This invention relates to an improved internal combustion engine.

As an object of the invention it is the aim 15 to provide a single piston valve internal combustion motor, which can be installed and constructed in such wise as to reduce the time, labor and material to a minimum.

Another object of the invention is to improve and simplify the construction of such motor, and to provide ball bearing mountings for the crank shaft and crank connection, and the eccentric shaft, so as to lessen the friction of said parts.

One of the features of the invention is to so construct and connect the cylinder to the frame of the engine, as to permit the parts to be easily and quickly assembled or disassembled with a minimum amount of labor 30 and time.

Another object of the invention is to provide improved means of connecting between the piston and the pitman rod of the crank, so as to relieve the crank and the pitman 35 rod of the sudden jar or impact incident to the explosion of the charge.

In practical fields the details of construction may necessitate alterations, falling within the scope of what is claimed.

The invention comprises further features and combination of parts, as hereinafter set forth, shown in the drawings and claimed.

In the drawings:—Figure 1 is a view in side elevation showing the motor constructed 45 on a horizontal plane. Fig. 2 is a longitudinal sectional view. Fig. 3 is a cross sectional view through the frame, showing how the frame is connected to the base. Fig. 4 is a horizontal sectional view through the connection between the piston and the pitman rod. Fig. 5 is a sectional view showing the engine constructed as a vertical motor.

Referring to the drawings, more particularly to Figs. 1 and 2, the numeral 1 designates the base, the forward portion of which is provided with a dove-tailed recess 2 for

the reception of a dove-tailed part 3 of the forward supporting standard 4, which supports the forward end of the cylinder 5.

The rear portion of the base 1 is provided 60 with elongated dove-tailed grooves or recesses 6 for the reception of the lower part 7 of the sides 8 of the frame of the motor. The end portion 9 of the cylinder 5 is constructed with a flange 10, through which 65 screw bolts 11 pass for fastening the flange to the edges 12 of the sides 8 of the frame, which structure together with the forward supporting standard supports the cylinder 70 firmly in position. By this improved structure the cylinder and the frame may be easily assembled and disassembled, as well as easily and quickly permitting the other parts of the motor to be disassembled or assembled.

Mounted in ball bearings 14 of the sides 75 of the frame is a crank shaft 15 provided with a crank 17 and a sprocket 18 at one end, which is keyed at 19 to said shaft. Also mounted in ball bearings 20 of the sides 80 of said frame is a shaft 21 having an eccentric 22 and a spur gear 23. A sprocket chain 24 passes about the sprocket 23 and the sprocket 18 as shown. The cylinder 5 is provided with a combustion chamber 26, there being inlet and exhaust from the combustion chamber to the piston valve chamber 27, said inlet and exhaust ports being designated by the numerals 28 and 29. The head 30 of the cylinder has the usual sparking plug 31. The mixture enters the piston 90 valve chamber from any suitable source (not shown), through the intake port 32, while the utilized gases pass from the cylinder 27 to the atmosphere through the exhaust port 33. Mounted in the piston valve casing 27 is a piston 34, the rod 35 of which passes through the packing box 36 and is connected at 37 to the pitman rod 38, which is provided with an eccentric strap 39, engaging 100 about the eccentric 22.

The piston 41 in the cylinder 5 is of the usual hollow construction, and provided with the usual piston rings 42. The opposite sides of the interior of the hollow piston 41 are provided with guides 43 to receive the member 44, there being upon the opposite sides of each member stout coil springs 45, which engage the end of each guide, thereby yieldably mounting said members. Journaled in the members is a 105 pivot pin 46, on which sleeves 47 are mounted, which hold the pitman rod 48 substan-

2
 tially centered upon the pivot pin. The pitman rod 48 is in turn connected to the crank of the crank shaft, by means of ball bearing connections, as shown at 50, the cap plate 51 acting to hold the parts in their proper places. It will be observed that as the charge is ignited, the yieldable connections between the pitman 48 and the piston of the cylinder 5 will relieve the sudden jar or impact between the pitman and the crank shaft.

Referring to Fig. 2 it is to be understood that a charge has been fired, the piston 41 having been forced to the position shown in full lines, the piston 34 having been moved as shown also in full lines. The momentum carries the piston 41 forwardly, thereby forcing the remaining utilized gases through the exhaust 29, the piston 34 having been moved to the dotted line position *g*. Then when the piston 41 travels back again, the port 28 is uncovered, and a charge is drawn from behind the piston 34 into the combustion chamber, the piston 34 having been moved to the dotted line position *s*. The piston 41 then travels forward again and compresses the charge, and at the same time the piston 34 moves back to the dotted line position *g*, closing the port 28. Immediately following the compression of the charge the charge is ignited, forcing the piston 41 back-

wardly, and in so doing the port 29 is uncovered, by the piston 34 moving to the full line position, thereby allowing the utilized gases to escape. These cycles of operations are consecutively repeated, as the engine continuously operates.

The invention having been set forth, what is claimed as new and useful is:

In an internal combustion engine, a piston therefor operable in the combustion chamber of said engine, said piston being cylindrical and hollow and having one end open, the other end closed, the interior wall of the hollow piston having diametrically opposite elongated guide grooves machined in the wall, members mounted in the guide grooves, coil springs upon opposite sides of each member and coöperating with the end walls of the guide groove, a pivot pin having its opposite ends fitting in said members, sleeves on the pin, and a pitman pivoted to the pin between the sleeves.

In testimony whereof I have signed my name to this specification in the presence of two subscribing witnesses.

JOHN ANDREW KREMER.
